UNITED STATES PATENT OFFICE.

JAMES C. MOCK, OF DETROIT, MICHIGAN.

PIPE-CARRIER SUPPORT.

1,247,316.

Specification of Letters Patent. Patented Nov. 20, 1917.

Application filed November 13, 1915. Serial No. 61,386.

To all whom it may concern:

Be it known that I, JAMES C. MOCK, a citizen of the United States, residing at Detroit, in the county of Wayne and State 5 of Michigan, have invented a new and useful Pipe-Carrier Support, of which the following is a specification.

This invention relates to supporting means for the carriers of the pipes employed to shift railway switch points and signals, and its object is to provide devices of this character which will permit all necessary lateral adjustment of the pipe carriers.

15 This invention consists, in combination with proper foundations which are preferably of concrete, of metal pedestals secured to the foundations, longitudinally slidable slotted bars or pipes carried by 20 the pedestals, and pipe carriers mounted on said bars or pipes and slidable longitudinally thereof, the parts being so arranged and constructed that the same bolts that 25 secure the slotted bars or pipes to the pedestals may also secure carriers to the bars or pipes.

In the accompanying drawings, Figure 1 is a front elevation and Fig. 2 an end elevation of a group of pipe carriers. Fig. 3 is 30 a cross section of a foundation showing a pedestal embedded therein. Fig. 4 is a front elevation of this pedestal. Figs. 5 and 6 are perspective views of anchor bars. Fig. 7 is a view, partly in section, showing a 35 modified form of pedestal. Fig. 8 is a view of the same pedestal adapted for round hollow anchor bars. Fig. 9 is an elevation of another form of pedestal. Fig. 10 is a plan thereof. Fig. 11 is an elevation of one 40 side of a slightly modified form of pedestal. Fig. 12 is an end view of another form of anchor bar. Fig. 13 is a perspective of another form of anchor bar.

Similar reference characters refer to like 45 parts throughout the several views.

In modern railway train control systems, groups of switch points are often operated from a tower conveniently located, and the connections between these switch points and 50 the operating levers within the tower consist largely of ordinary pipes supported by rollers properly mounted in carriers. In Figs. 1 and 2, these pipes are designated 1, the rollers 2 and the carriers 3. The rollers 55 have short trunnions 4 that extend into and

travel laterally in transverse slots 5 in the carriers and thus permit the rotation of the rollers. After the first pair of carriers are in place, each additional pipe requires only one additional carrier.

Instead of anchoring these carriers directly to the foundations 6, I have provided supporting means for the carriers that are so constructed as to provide for lateral adjustments of these carriers. Mounted on, embedded in, or otherwise secured to the foundations are pedestals, preferably although not necessarily in pairs, of which various forms are shown in the drawings. In Figs. 3 and 4, the pedestal 7 is shown to consist of jaws 8 connected by the cross bars 9 and 10. These jaws are formed by grooving the pedestal to receive the anchor bars 12, shown in Figs. 3 and 4 to consist of slotted tubes and, as indicated in Figs. 5 and 6, these tubes may have a continuous slot 14 or a series of short slots 15.

Bolts 16 are employed to secure the carriers to the anchor bars and also to secure at least one carrier to the pedestal, as indicated in Figs. 3 and 4. It will be seen that where a larger number of pipes 1 are to be installed, it is merely necessary to add additional foundations and pedestals and bridge the spaces between them by additional or longer anchor bars.

Where the foundations are already in place, pedestals 18 may be secured thereto by means of bolts 19 and a cross bar 20 or by the bolts 19 alone, as indicated in Figs. 9 and 10. If the anchor bars are to be in the form of beveled bars 22, as indicated in Fig. 11, the groove 23 in the pedestal will be properly modified therefor. If desired, the parts 10 of the pedestals shown in Figs. 3 and 4 may be omitted, and pedestals 25 such as shown in Fig. 7 employed, the grooves 26 being adapted to receive the angle bars 22 or, if desired, the pedestals may be formed with grooves 27 to receive 10 the round anchor bars 12. The anchor bars 28 may be formed with grooves 29 in their lower sides, as indicated in Fig. 12, if desired, to prevent the bolts from turning.

In Fig. 13 is shown an anchor bar 31 formed with notches 32 in which the jaws of the pedestals may engage when the pedestal, anchor bars and carriers are secured together by means of the bolts 16 extending up through the slots 33. This anchor bar 11

will be immovable endwise after being secured in place.

Many other changes in the details and proportions of this construction may be made without departing from the spirit of my invention.

I claim:—

1. In a pipe carrier support, the combination of a foundation, a pedestal secured thereto and having grooves extending at right angles to the pipe to be supported, anchor bars slidably mounted in said grooves, a carrier mounted on said anchor bars, and bolts to secure the carrier and anchor bars in position on the pedestal.
2. In a pipe carrier support, the combination of a pair of foundations, a pedestal for each foundation and secured thereto and having grooves extending at right angles to the pipes to be supported, a pair of longitudinally slotted anchor bars slidably mounted in said grooves in the pedestals, carriers mounted on said anchor bars, and bolts to secure the carriers to said anchor bars.
3. In a pipe carrier support, the combination of a pair of foundations, a pedestal for each foundation and secured thereto and having grooves extending at right angles to the pipes to be supported, a pair of longitudinally slotted anchor bars slidably mounted in said grooves in the pedestals, carriers mounted on said anchor bars, and bolts to secure one of the carriers and the anchor bars in position on one of the pedestals.
4. In a pipe carrier support, the combination of a pair of foundations, a pair of pedestals for each foundation and secured thereto and each provided with a pair of transverse grooves, a pair of anchor bars mounted in said grooves and having longitudinal slots, a plurality of pipe carriers mounted on said anchor bars, and bolts extending through the slots in the anchor bars and into said carriers to secure the carriers in position, one of said carriers also engaging a

pedestal and thereby securing the anchor bars in position.

5. In a carrier support, the combination of a foundation, a pedestal secured thereto consisting of a pair of cross bars, one above the other, and jaws connected to the cross bars, anchor bars extending through the jaws, a plurality of carriers mounted on said anchor bars, and means to secure the carriers in position relative to the pedestal.

6. In a pipe carrier support, the combination of a foundation, a pedestal secured thereto, a pair of anchor bars mounted on the pedestal, a plurality of carriers mounted on the anchor bars, and a pair of bolts for each carrier to secure the carrier to the anchor bars, one pair of said bolts also engaging the pedestal and thereby securing the anchor bars and a carrier in position in said pedestal.

7. In a pipe carrier support, the combination of a foundation, a pedestal secured thereto, a pair of anchor bars mounted on the pedestal, a carrier mounted on the anchor bars, and a pair of bolts engaging the pedestal, anchor bars and carrier to secure the anchor bars and carrier in position on the pedestal.

8. In a carrier support, the combination of a foundation, a pedestal secured thereto having a jaw at each end, anchor bars extending through the jaws, a plurality of carriers mounted on said anchor bars, and means to secure the carriers in position on the anchor bars.

9. In a carrier support, the combination of a foundation, a pedestal secured thereto having a jaw at each end, slid anchor bars one extending through each of said jaws, a carrier mounted on said anchor bars, and a bolt extending through each of said anchor bars and said carrier to secure the carrier and anchor bars in position relative to the pedestal.

In testimony whereof I sign this specification.

JAMES C. MOCK.
